UNITED STATES PATENT OFFICE.

LOUIS T. MEDHOLDT, OF ROCKFORD, ILLINOIS, ASSIGNOR TO MATTISON MACHINE WORKS, OF ROCKFORD, ILLINOIS, A CORPORATION OF ILLINOIS.

CUTTER HEAD.

Application filed September 17, 1924. Serial No. 738,116.

The invention has general reference to 5 woodworking machines of the type usually designated "moulders," and the primary aim has been to produce a cutter head of advanced construction having improved means for securing the head upon the cutter shaft or spindle.

Moulders as commonly constructed embody 10 side cutter heads mounted to rotate on vertical spindles and top and bottom heads mounted to rotate on horizontal spindles; and the heads are round or square in shape depending upon the character of the work to be operated upon. The horizontal spindles are made of larger 15 diameter than the vertical spindles, so that cutter heads as previously constructed are not susceptible to interchangeability.

One object of my invention is to provide 20 a cutter head with clamping means whereby it may be mounted upon either the vertical or horizontal spindles as desired.

Another object is to provide clamping means for the cutter heads, whereby the heads may be readily secured upon the vertical spindles of the moulders in a predetermined position thereon.

A further object is to provide improved 30 clamping means for the cutter heads whereby they may be readily secured upon the horizontal spindles, and which will permit the withdrawal of blade fastening bolts without disturbing the position of the cutter head axially of the spindle.

The objects of the invention thus set forth 35 and other advantages, are attained by the construction and arrangement illustrated in the accompanying drawings and hereinafter fully described, but it is to be understood that I contemplate that various changes in such 40 construction may be made by those skilled in the art without departing from the spirit and scope of the invention as expressed in the appended claims.

Figure 1 of the drawings is a side elevational view of a square cutter head secured upon the upper end portion of a vertically disposed spindle such as is employed for supporting the side cutter in woodworking machinery.

Fig. 2 is a vertical sectional view through the same.

Fig. 3 is a plan view of the head.

Fig. 4 is a horizontal sectional view taken in the plane of line 4—4 of Fig. 2.

Fig. 5 is a perspective view of a square

cutter head equipped with clamping means for fastening it upon a horizontal spindle.

Fig. 6 is a side elevation of the same.

Figs. 7 and 8 are transverse sectional views taken respectively in the planes of lines 7—7 and 8—8 of Fig. 6.

Fig. 9 is a longitudinal section taken in the plane of line 9—9 of Fig. 7.

The cutter head selected for purposes of illustration is of the so-called square type. 65 It comprises a body 5 (Figs. 1 to 4 inclusive) approximately rectangular in form and of substantial length. Centrally thereof it is formed with a bore 6 and in its outer side faces it has under-cut T slots 5^a for receiving 70 the heads of bolts 5^b whereby the cutter blades (one being shown in broken lines in Fig. 4) may be secured in a well known manner.

Referring first to Figs. 1 to 4, 7 designates the upper end portion of a vertical supporting 75 shaft or spindle. The bore 6 in the head is made of a diameter somewhat greater than the diameter of the spindle to accommodate the means whereby the head is clamped upon the spindle.

Said clamping means comprises a pair of 80 clamping members 8 seated respectively in counterbored recesses 9 in the opposite ends of the body 5. These members are approximately circular in form but have outer peripheries cut away along lines coinciding with the bottoms of the T-slots 5^a so as to clear the heads of the blade securing bolts 5^b. To receive the members 8, the body is provided at each end with a recess 9 of a depth 90 approximately equal to the length of the member; and the members are rigidly secured against rotary movement relative to the body by means of one or more pins 10 (two being herein shown). 95

The clamping members 8 are in the form of rings split at 8^a (Fig. 1) and shaped to provide inner conical bearing surfaces 11 inclined inwardly and outwardly toward the ends of the body; and coacting with said surfaces 11 of the members 8 are similarly inclined conical surfaces 12 on a pair of clamping members 13 and 13' fitting into the members 8. Each of said ring members 13 and 13' is in the form of a ring split or severed 100 at one side, as indicated at 14 and 14', so as to be capable of contracting when forced into its coacting clamping member 8.

The lower clamping member 13' is, in the present instance, shown as being formed in-

tegral with a sleeve 15 of a length somewhat greater than the length of the body and of a diameter such as to be capable of passing loosely through the central bore 6 in the body. 5 The upper portion of said sleeve is screw-threaded and the portion projecting from the upper end of the body has mounted thereon a nut 16 which is adapted to engage directly with the clamping ring 13, to force it into 10 the conical member 8, the nut operating at the same time through the sleeve 15 to draw the clamping ring 13' at the lower end of the sleeve into the conically faced member 8 at the lower end of the body. The sleeve 15 is 15 provided with diametrically opposed slots 17 extending throughout the major portion of the length of the sleeve, the slot 14' in the lower clamping member 13' being continued through the lower end of the sleeve and 20 merged into one of the slots 17. It will thus be seen that as the clamping rings 13 and 13' are forced into their respective bearing members 8 the contraction of such rings effects a like contraction of the sleeve and thus 25 the sleeve is clamped upon the spindle. Also, the clamping members 8 are expanded into engagement with their recesses 9, so that the body is firmly clamped upon the spindle. In order to insure that the sleeve shall clamp 30 the spindle uniformly at opposite ends of the body, the inner periphery of the sleeve is cut away near its central portion as indicated at 18.

In addition to the frictional engagement 35 thus provided between the sleeve and the spindle, a driving pin 19 may be employed, which pin is secured in the lower end of the sleeve and has its head projecting radially of the sleeve so as to enter a groove 20 formed 40 in the periphery of the spindle longitudinally thereof.

The nut 16 is constructed so as to provide 45 means for positioning the cutter head on the spindle and means for locking the clamping means in operative position. Thus it is made in the form of a cap having a central bore 21 therein, terminating short of the upper side of the cap so as to form a top wall 22. The lower portion of this bore is internally-screw-threaded as at 23 so as to coact with the screw-threaded upper end of the sleeve 15. A screw 24 is mounted in the top wall 22 of the cap and projects into the bore for engagement 50 with the upper end of the spindle. The screw is equipped with a lock nut 25 for holding it in set position.

In mounting the cutter, the completely assembled head is slipped down over the spindle until the stop screw engages the upper exposed end of the spindle, thus determining the position of the cutter head, and the nut is then turned to operate the two clamping members 8, and the clamping members 13 and 13' and the ends of the sleeve 15.

60 One side of the nut 16 is constructed to

form an arcuate portion 26 having one end free so as to be movable independently of the nut proper after the clamping operation, to effect a locking of the nut in position. This portion 26 is formed by slotting the nut 70 diametrically thereof as shown at 27 and also longitudinally as at 28, the two slots thus formed serving to free the portion 26 from the body of the nut so as to render it capable of being turned slightly with a yielding of 75 the metal to effect a locking of the nut on the sleeve.

To facilitate the manipulation of the nut 16 it may be provided with the usual radially disposed holes 29 in its periphery to receive 80 a spanner wrench; and the means for operating the arcuate portion 26 comprises, a screw 30 arranged approximately tangentially of the nut across the slot 28 and having a squared head 31 entered in a recess 32 formed 85 in the peripheral face of the nut.

It will be observed that the nut 16 not only serves to operate the clamping means but it provides in a unitary structure an adjustable stop member whereby to facilitate the placing of the head in proper position on the spindle, and also a means for locking the nut in clamped position. Moreover, it will be seen that to remove the cutter blades from the head it is only necessary to loosen the nuts 95 on the bolts 5 and the bolts may be removed without removing the head by sliding them downwardly out of their T slots as is permitted by the special construction of the bearing members 8. In prior constructions 100 it has been necessary to remove and disassemble the cutter head to permit the removal of the clamping bolts.

Referring now to Figs. 5 to 9, I have shown my improved cutter head in the form in 105 which it is clamped on the horizontal spindles. Inasmuch as the latter are of larger diameter than the vertical spindles, as above indicated, I remove the inner clamping sleeve 15 and employ similar clamping units at each 110 end of the head, it being apparent that both ends of the head when horizontally disposed are readily accessible. Each of these units comprises a pair of coaxial clamping members 33 and 34. The member 33 is in the form 115 of a sleeve fitting over the spindle and entered in a counterbored recess 35 in the end of the cutter body 5'. At its inner end the sleeve is shaped to provide a conical bearing surface 36 and its outer portion is threaded to receive a clamping nut 37 set at 37°. The other clamping member 34 of each unit is in the form of a collar fitting over the sleeve 33 and having inwardly projecting portions 34a shaped at their inner ends to form conical 125 bearing surfaces 38 arranged to coact with the surface 36 on the sleeve. The latter is held against rotation in the body by a pin 39 driven into the bottom of the recess 35 and adapted to engage in a hole 40 in the inner 130

end of the sleeve. In one side of the sleeve is a slit 41 and equidistantly spaced about the sleeve are a plurality of saw cuts 42 (Fig. 7). This construction permits a contraction 5 of the sleeve onto the spindle. Similarly, the collar 34 is slit at 43 to permit it to expand against the wall of the recess 35. Thus, it will be seen, by tightening the nuts 37 on opposite ends of the head, the sleeve 33 will 10 be contracted into engagement with the spindle and the collar 34 will be expanded into engagement with the cutter body, effectually clamping the head on the spindle.

As in the case of the vertical spindle, it is 15 desirable that the clamping bolts for the blades be removable without disturbing or removing the head. To this end each of the sleeves 33 and collars 34 are made of a length such that the nuts 37 are spaced some distance 20 from the ends of the cutter body. Moreover, the inner end of the sleeve is cut away on its peripheral face to form flat sides 44 disposed substantially flush with the bottoms of the T-slots 5^a (Fig. 7), as are also the 25 peripheral faces of the collar portions 34^a and the periphery of the collar 34 at its outer end, as shown at 45 (Figs. 5 and 6). This renders it possible to remove the clamping bolts by sliding them endwise in their slots 30 5^a, the nuts 37 being spaced far enough from the ends of the body to permit the withdrawal of the bolt heads as shown in Fig. 5. Consequently, when for any reason a blade 35 is removed from the cutter head, the clamping bolts thus rendered superfluous can also be quickly and easily removed.

It will be understood that the cutter bodies when constructed in accordance with my invention may be used either on the vertical 40 spindles or the horizontal spindles at will, notwithstanding the fact that they vary in diameters. In the case of the vertical spindles the construction shown in Figs. 1 to 5 is employed, the central sleeve 15 rendering 45 possible the use of a single clamping nut 16, and also the use of a body having an internal bore larger than the spindle. In the case of the horizontal spindles, the larger bore of the body conforms to the diameter of 50 the spindle and in this instance, because both ends of the head are readily accessible, the continuous operating sleeve 15 may be dispensed with. In either case, the blade fastening bolts may be removed without removing 55 or disassembling the head.

I claim as my invention:

1. The combination with a spindle, of a cutter head surrounding said spindle and comprising a body having a central bore extending therethrough, a pair of conically surfaced clamping members mounted in the body at opposite ends thereof, a second pair of complementary conically surfaced clamping members adapted to engage the first clamping members to effect a contraction of one of 60 said pairs of clamping members onto the spindle, and means for operating the clamping members including a nut in the form of a cap having a stop screw adapted to engage the spindle and means for locking the nut 65 onto one of the clamping members.

2. A cutter head comprising a body, and means for clamping the body on a spindle including a nut encircling the spindle and having an adjustable axial stop member for initially 70 positioning the cutter on the spindle and means including a screw for locking the nut in position.

3. A cutter head comprising, a body, means for clamping the body on a spindle including 75 a nut encircling the spindle and having an upper end wall and a movable side portion, and a stop screw mounted in said wall and adapted to engage with the upper end of the spindle to position the head thereon, said side 80 portion having means for moving it relative to said top wall to lock the nut in operative 85 position.

4. A cutter head having a body and means for clamping the body onto a supporting 90 spindle comprising, a pair of clamping members at opposite ends of the body, a threaded sleeve integral with one of said members, and a clamping nut having a top wall and an independently movable arcuate threaded side 95 portion, and means for forcing said threaded portion into locking engagement with the threaded sleeve.

5. A cutter head having a body and means for clamping the body onto a supporting 100 spindle comprising, a pair of clamping members at one end of the body one of said members having a threaded portion, and a clamping nut having a closed end wall and an arcuate threaded portion movable into locking engagement with said threaded portion.

In testimony whereof, I have hereunto affixed my signature.

LOUIS T. MEDHOLDT.
